UNITED STATES PATENT OFFICE.

JUDSON A. LAMON, OF MONTCLAIR, NEW JERSEY, ASSIGNOR TO MCCORD AND COMPANY, OF CHICAGO, ILLINOIS, A CORPORATION OF NEW JERSEY.

JOURNAL-BOX LID.

1,109,074.

Specification of Letters Patent. Patented Sept. 1, 1914.

Application filed August 26, 1912. Serial No. 716,952.

To all whom it may concern:

Be it known that I, JUDSON A. LAMON, a citizen of the United States, residing at Montclair, in the county of Essex and State of New Jersey, have invented certain new and useful Improvements in Journal-Box Lids; and I do hereby declare the following to be a full, clear, and exact description of the invention, such as will enable others skilled in the art to which it appertains to make and use the same.

My invention relates to journal box lids and has for its object to provide an improved pivot pin and pin securing devices therefor.

To the above ends, the invention consists of the novel construction and combination of devices hereinafter described and defined in the claims.

20 In the accompanying drawings, which illustrate the invention, like characters indicate like parts throughout the several views.

Referring to the drawings, Figure 1 is a view in front elevation showing the journal box lid and pin designed and arranged in accordance with my invention, some parts being broken away; Fig. 2 is a right side elevation of the parts shown in Fig. 1; and Fig. 3 is a section taken on the line $x^x x^x$ 25 on Fig. 2, some parts being broken away; Fig. 4 is a left side elevation of the lid with parts thereof being broken away.

The body 1 of the journal box lid is provided with the customary spring housing or hood 2 and hinge lugs 3, which parts are cast integral.

The numeral 4 indicates the pivot pin or hinge bolt which serves to pivotally connect the lid to the customary lug provided on top 40 of the journal box, but not shown in the drawings. Hitherto, it has been customary to rivet the ends of the pivot pin in the hinge lugs of the journal box lid, and with such construction, it is a difficult matter to 45 remove the lid and to apply another lid or to replace the same lid, or to apply a new pin, because such operations require furnace hammers, etc., around the yard. My invention provides a very simple and highly efficient means, making it possible to easily remove the pin and to replace another pin, simply by the use of a hammer.

The invention consists in providing the lid with pin retaining lugs adapted to be 50 alined with the ends of the pin when it is

applied through the hinge lugs 3 of the lid. These lugs, which are indicated by the numerals 5 and 6, are cast integral with the lid. The lid will preferably be made from cast steel or from malleable iron so that either one or both of the said lugs may be easily bent laterally from a position indicated by dotted lines into a position indicated by full lines in Fig. 2, or vice versa. It is not necessary, however, to bend the lug 5, 55 but the lug 6 should normally occupy a position indicated by dotted lines in Fig. 2, which is out of lateral alinement with the pin seats provided in the hinge lugs 3. To cause the pin to move with the lid, the pin 4 is notched in one end, so that it is adapted to straddle the lug 5. When the pin 4 is inserted, as shown in Fig. 1, and interlocked with the lug 5 against rotation, in respect to the lid, or for rotation with the said lid, the 60 lug 6, by a quite light blow of a hammer, may be bent into alinement with the pin, as shown by full lines in Fig. 2. When the said lug 6 is bent, as stated, it will positively secure the pin in an operative position and will hold the same interlocked to the lug 5. When it is desired to remove the pin, it is only necessary to bend the lug 6 back to its dotted line position in Fig. 2, so as to permit the pin to be moved endwise 65 out of its seats in the hinge lugs.

This device, while of very small cost, has been found highly efficient for the purposes had in view, and as is obvious, makes it an easy matter to apply pins to the lids or remove the same from the lids.

You will note that in all of the forms of the device shown by the applicant, the retaining lug is an element distinct from the hinge lug. By the expression "distinct 70 from" is meant that the said element is not the hinge lug itself but is a different element from the hinge lug.

What I claim is:

1. A journal box-lid having a hinge lug 75 and a hinge bolt seated therein and having also a retaining lug capable of being bent in a plane that transversely intersects the axis of said bolt, from a position out of the line of axial movement of said bolt into a 80 position within the line of movement of said bolt, for retaining the same in working position.

2. A journal box lid having hinge lugs 85 and a hinge bolt seated therein and remov- 90

- able therefrom by endwise movement, said lid having integral bolt retaining lugs alined with the ends of said bolt and at least one of which retaining lugs is adapted to be bent 5 in a plane that transversely intersects the axis of said bolt, from a position out of line of axial movement of said bolt into the line of movement of said bolt for retaining said bolt in working position, said retaining lug 10 being an element distinct from said hinge lug.
3. A journal box lid having hinge lugs and bolt seats therein, said lid having integral retaining lugs located axially outward of said hinge lugs, a hinge bolt seated in the said hinge lugs and interlocked to one of said retaining lugs and thereby held for rotation with said lid, and the other of which retaining lugs is capable of being bent 15 in a plane that transversely intersects the axis of said bolt, from a position out of line of axial movement of said bolt into the line of movement of said bolt, said retaining lug 20

being an element distinct from said hinge lug. 4. A journal box lid having hinge lugs with bolt seats therein, and a hinge bolt applicable to and movable from said hinge lugs by endwise movement, said lid also having integral retaining lugs located axially outward of said hinge lugs, at least one of which retaining lugs is capable of being bent 25 in a plane that transversely intersects the axis of said bolt, to and from alinement with said hinge bolt, and said bolt having a notch at one end embracing one of the said hinge lugs to hold said pin for rotation with said lid, said retaining lug being an element distinct from said hinge lug.

In testimony whereof I affix my signature 30 in presence of two witnesses.

JUDSON A. LAMON.
